ABSTRACT

Substituted carboximidic acid esters of 7-(2-mercaptopacetamido) cephalosporanic derivatives which are prepared by the reaction of the appropriately substituted thioamide with an appropriate 7-(2-haloacetamido) cephalosporanic acid derivative. The compounds are antibacterial agents.

**SUBSTITUTED CARBOXIMIDIC ACID ESTERS OF
7-(2-MERCAPTOACETAMIDO)
CEPHALOSPORANIC ACID DERIVATIVES**

5

DESCRIPTION OF THE INVENTION

In accordance with this invention there is provided antibacterial agents of the formula:

wherein

A is a member selected from the group consisting of alkyl of 1 to 6 carbon atoms;

in which R³ is alkyl of 1 to 6 carbon atoms; arylcarboxamidomethyl of 8 to 12 carbon atoms; alkanoylamidomethyl of 3 to 8 carbon atoms; α -cyanobenzyl;

in which R⁴ is hydrogen, dialkylamino of 2 to 6 carbon atoms or halo and p is 0 or 1;

in which X is O, S or NH;

where R⁵ is hydrogen, alkyl of 1 to 6 carbon atoms and phenyl; and

B is a member selected from the group consisting of H , alkanoyloxy of 2 to 6 carbon atoms,

or, when taken with the 3-carboxy group,

M is a member selected from the group consisting of H , an alkali metal and NH_4^+ ;

R¹ is a member selected from the group consisting of H , alkyl of 1 to 6 carbon atoms and aryl of 6 to 10 carbon atoms;

R² is a member selected from the group consisting of H , alkyl of 1 to 6 carbon atoms and aryl of 6 to 8 carbon atoms;

n is one of the integers 0, 1 or 2; and the pharmaceutically acceptable acid addition salts thereof.

The compounds of this invention are prepared by reaction of an appropriately substituted thioamide with an appropriate 7-form, 2-haloacetamido)cephalosporanic acid derivative. The reactants are dissolved in acetone and stirred at a temperature generally between 10° and 25°C. for a period of from about 4 hours to 24 hours. Any solid material is removed from the reaction solution by filtration and the solvent is removed under reduced pressure at a temperature below 30°C. The product is then triturated with diethyl ether and the product is recovered as a polymorphous material. For ease in processing, the products are generally recovered in the hydrohalide addition salt form frequently with small amounts of solvent, the latter being readily removed by further vacuum stripping of the product. The free bases are readily formed by neutralization of the hydrohalide by conventional techniques.

As used throughout this specification, the term "alkyl" is intended to embrace univalent aliphatic hydrocarbon radicals such as methyl, ethyl, propyl, i-propyl, butyl, i-butyl, amyl and hexyl. The expression "arylcarboxamidomethyl" of 8 to 12 carbon atoms; is intended to embrace such radicals as benzoylamidomethyl groups in which from 1 to 5 alkyl groups may be present containing a total of 4 carbon atoms. The expression "alkanoylamidomethyl" of 3 to 8 carbon atoms: is intended to embrace those unbranched lower fatty acid

amidomethyl groups in which the fatty acid contains from 2 to 7 carbon atoms. The term "halo" is intended to embrace chlorine, bromine, iodine or fluorine, preferably chlorine or bromine. The "alkali metals" intended to be embraced are sodium and potassium. The term "aryl" is intended to embrace those monovalent aromatic hydrocarbons whose single valence bond belongs to the nucleus such as phenyl, naphthyl, tolyl, ethylphenyl and dimethylphenyl, as limited by the recited number of carbon atoms.

The preferred compounds of this invention are those derived from readily available reactants which are most economical to produce and efficacious in use, presenting the formula:

wherein

A is a member selected from the group consisting of alkyl of 1 to 6 carbon atoms;

in which R³ is alkyl of 1 to 6 carbon atoms; benzamidomethyl; acetamidomethyl; α -cyanobenzyl; aryl of 6 to 8 carbon atoms dimethylaminophenyl; phenylthio;

;

;

;

and

50

B is a member selected from the group consisting of —H and acetoxy;

M is a member selected from the group consisting of —H, an alkali metal and —NH₃⁺;

R¹ is a member selected from the group consisting of —H, alkyl of 1 to 6 carbon atoms and aryl of 6 to 10 carbon atoms;

R² is a member selected from the group consisting of —H, alkyl of 1 to 6 carbon atoms and aryl of 6 to 8 carbon atoms;

and the pharmaceutically acceptable acid addition salts thereof.

The compounds of this invention are active antibacterial agents, effective against gram-positive and gram-negative bacteria as well as penicillin resistant staphylococcus. The activity of the compounds was established by treating various bacteria colonies grown under controlled conditions with various concentra-

tions of aqueous solution of the compounds of this invention in accordance with the well known, scientifically accepted agar serial dilution testing technique, to determine the minimum inhibitory concentration (MIC) of each compound. Hence, the compounds of this invention, being effective in the control of bacterial infestations, are useful in the fields of comparative pharmacology and microbiology and for the control and comparative analysis of bacterial colonies. The compounds are to be used to inhibit the growth of bacteria in the conventional manner and by the known methods of utilizing cephalosporin derivatives.

The following examples illustrate the preparation of representative cephalosporin derivatives of this invention. The activity of each exemplified product is presented for those specific bacterial strains against which the compound exemplified was active at or below 250 micrograms per milliliter. The representative nature of the bacterial strains employed to demonstrate anti-bacterial activity are indicative of the broader applicability of the compounds disclosed herein in the control of bacterial infestations other than those specifically referred to in each of the following examples. The bacteria are named, followed by the specific strain and the concentration at which 100 percent inhibition occurred. The abbreviations for each bacterium are:

30	BA SU	Bacillus subtilis
	BO BR	Bordetella bronchiseptica
	EN AE	Enterobacter acrogenes
	ST AU	Staphylococcus aureus
	ES CO	Escherichia coli
	ES IN	Escherichia intermedia
	HE SP	Herellea species
	NE CA	Neisseria catarrhalis
	SA PA	Salmonella paratyphi
35	KL PN	Klebsiella pneumoniae
	PR VU	Proteus vulgaris

EXAMPLE 1

7-[2-(p-Dimethylamino-N-methylbenzimidoylthio)acetamido]cephalosporanic acid.

7-(2-Bromoacetamido)cephalosporanic acid (0.39 gram, 1 millimole) and p-dimethylamino-N-methylthiobenzamide (0.19 gram, 1 millimole) are dissolved in acetone. The solution is stirred at room temperature for four hours and stored in a refrigerator overnight. The solvent is removed and the residual solid (0.5 gram) is triturated with diethyl ether to yield the title compound as the hydrobromide salt.

Elemental Analysis for C₂₂H₂₆N₄O₆S₂HBr·1/2(C₂H₅)₂O:

EXAMPLE 18

7-(2-Mercaptoacetamido)cephalosporanic acid ester with N-phenylthiobenzimidic acid.

The procedure of Example 6 is repeated with the exception that N-phenylthiobenzamide is employed rather than N-phenylthioacetamide to obtain the title compound as the hydrobromide addition salt.

40

Elemental Analysis for $C_{25}H_{23}N_3O_6S_2 \cdot HBr \cdot 1/4(CH_3)_2O \cdot H_2O$

Calc'd: C, 48.25; H, 4.44; N, 6.49.

Found: C, 48.55; H, 4.25; N, 6.58.

EXAMPLE 19

7-(2-Mercaptoacetamido)cephalosporanic acid ester with 2-cyano-2-phenylthioacetimidic acid.

The procedure of Example 17 is repeated with the exception that 2-cyano-2-phenylthioacetamide is used as the reactant in lieu of 2-benzamidothioacetamide. The product is recovered as the hydrobromide addition salt.

Elemental Analysis for $C_{21}H_{20}N_3O_6S \cdot HBr \cdot 3H_2O \cdot 1/4(CH_3)_2CO \cdot 1/6(C_2H_5)_2O$

Calc'd: C, 41.43; H, 4.68; N, 8.62.

Found: C, 40.89; H, 3.99; N, 8.36.

EXAMPLE 20

7-(2-Mercaptoacetamido)cephalosporanic acid ester with phenyldithioimidocarbonic acid 7-phenyl ester.

7-(2-Bromoacetamido)cephalosporanic acid (0.79 gram, 2-millimole) and N,S-diphenyl-dithiocarbamate (Crosby and Niemann, J.A.C.S. 76, 4458-4463(1954) (0.49 gram, 2 millimole) and sodium bicarbonate (0.25 gram, 3 millimole) are dissolved in aqueous acetone 20 and heated in a water bath (60°C.) for 6 hours. After removing some insoluble material by filtration, the solvent is evaporated. Water is added to the residue and the resulting solution is acidified with 6N HCl. The precipitated solid is washed with water, dissolved in acetone, filtered and again evaporated. The solid (0.35 gram) is triturated with diethyl ether and recovered.

What is claimed is:

1. A compound of the formula:

wherein

A is a member selected from the group consisting of alkyl of 1 to 6 carbon atoms;

30 in which R³ is alkyl of 1 to 6 carbon atoms;

arylcarmidomethyl of 8 to 12 carbon atoms;

alkanoylamidomethyl of 3 to 8 carbon atoms;

α-cyanobenzyl;

40 in which R⁴ is hydrogen, dialkylamino of 2 to 6 carbon atoms or halo and p is 0 or 1;## EXAMPLE 21

7-(2-Mercapto-2-phenylacetamido)cephalosporanic acid diester with dithiooxalimide ester.

45

An acetone solution of dithiooxamide (0.12 gram, 1 millimole) and 7-(2-bromo-2-phenylacetamido)cephalosporanic acid (0.46 gram, 1 millimole) is stirred in an ice bath for 2 hours. Some insoluble material is removed by filtration and the acetone is evaporated. The residue is triturated with diethyl ether and the polymorphous product (0.45 gram) is recovered.

in which X is O, S or NH;

Elemental Analysis for $(\text{C}_{19}\text{H}_{18}\text{N}_3\text{O}_5\text{S}_2\text{HBr})_2 \cdot 1/2(\text{C}_2\text{H}_5)_2\text{O}$

Calc'd: C, 43.82; H, 3.95; N, 7.67.

Found: C, 44.58; H, 3.92; N, 7.30.

BO BR 4617 62.5

where R^5 is hydrogen, alkyl of 1 to 6 carbon atoms and phenyl; and

B is a member selected from the group consisting of —H, alkanoyloxy of 2 to 6 carbon atoms, or when taken with the 3-carboxy group,

M is a member selected from the group consisting of —H, an alkali metal and —NH4;

R^1 is a member selected from the group consisting of —H, alkyl of 1 to 6 carbon atoms and aryl of 6 to 10 carbon atoms;

R^2 is a member selected from the group consisting of —H, alkyl of 1 to 6 carbon atoms and aryl of 6 to 8 carbon atoms;

n is one of the integers 0, 1 or 2; and the pharmaceutically acceptable acid addition salts thereof.

2. A compound of claim 1 of the formula:

in which

A is a member selected from the group consisting of alkyl of 1 to 6 carbon atoms;

in which R^3 is alkyl of 1 to 6 carbon atoms; benzamidomethyl; acetamidomethyl;

α -cyanobenzyl; phenyl; p-chlorophenyl; dimethylaminophenyl; phenylthio;

and

B is a member selected from the group consisting of —H and acetoxy;

M is a member selected from the group consisting of —H, an alkali metal and —NH4;

R^1 is a member selected from the group consisting of —H, alkyl of 1 to 6 carbon atoms, phenyl, tolyl, ethylphenyl, dimethylphenyl and naphthyl;

R^2 is a member selected from the group consisting of —H, alkyl of 1 to 6 carbon atoms, phenyl, tolyl, dimethylphenyl and ethylphenyl; and the pharmaceutically acceptable acid addition salts thereof.

3. The compound of claim 1 which is 7-[2-(p-dimethylamino-N-methylbenzimidoylthio)acetamido]cephalosporanic acid.

4. The compound of claim 1 which is 7-[2-(p-chlorobenzimidoylthio)acetamido]cephalosporanic acid.

5. The compound of claim 1 which is 7-[2-(acetimidoylthio) acetamido]cephalosporanic acid.

6. The compound of claim 1 which is 7-[2-mercaptopacetamido]cephalosporanic acid ester with thioisonicotinimidic acid.

7. The compound of claim 1 which is 7-(2-mercaptopacetamido)cephalosporanic acid ester with thioisonicotinimidic acid.

8. The compound of claim 1 which is 7-(2-mercaptopacetamido)cephalosporanic acid ester with N-(1-naphthyl)thioacetimidic acid.

9. The compound of claim 1 which is 7-(2-mercaptopacetamido)cephalosporanic acid ester with thio-2-thiophencarboximidic acid.

10. The compound of claim 1 which is 7-(2-mercaptopacetamido)-3-methyl-8-oxo-5-thia-1-azabicyclo[4.2.0]oct-2-ene-2-carboxylic acid ester with thio-2-thiophencarboximidic acid.

11. The compound of claim 1 which is 7-(2-mercaptopacetamido)-3-methyl-8-oxo-5-thia-1-azabicyclo[4.2.0]oct-2-ene-2-carboxylic acid ester with thionicotinimidic acid.

12. The compound of claim 1 which is 7-(2-mercaptopacetamido)cephalosporanic acid ester with N-(1-naphthyl)thioacetimidic acid.

13. The compound of claim 1 which is 7-(2-mercaptopacetamido)acid ester with 5-oxo-3-phenyl-2-pyrazoline-1-carboximidothioic acid.

14. The compound of claim 1 which is 7-(2-mercaptopacetamido)cephalosporanic acid ester with 3-thio-2-furancarboximidic acid.

15. The compound of claim 1 which is 7-(2-mercaptopacetamido)cephalosporanic acid ester with 3-iminothiobutyrimidic acid.

16. The compound of claim 1 which is 7-(2-mercaptopacetamido)cephalosporanic acid ester with 2-benzamidothioacetimidic acid.

17. The compound of claim 1 which is 7-(2-mercaptopacetamido)cephalosporanic acid ester with N-phenylthioacetimidic acid.

18. The compound of claim 1 which is 7-(2-mercaptopacetamido)cephalosporanic acid ester with 3-iminothiobutyrimidic acid.

19. The compound of claim 1 which is 7-(2-mercaptopacetamido)cephalosporanic acid ester with N-phenylthioacetimidic acid.

20. The compound of claim 1 which is 7-(2-mercaptopacetamido)cephalosporanic acid ester with 2-cyano-2-phenylthioacetimidic acid.

21. The compound of claim 1 which is 7-(2-mercaptop-

15

to-2-phenylacetamido)cephalosporanic acid ester with 2-acetamidothioacetimidic acid.

22. The compound of claim 1 which is 7-(2-mercaptopacetamido) cephalosporanic acid ester with phenyl-dithioimidocarbonic acid 7-phenyl ester.

5

16

23. The compound of claim 1 which is 7-(2-phenylacetamido) cephalosporanic acid diester with dithiooxalimidic ester.
